UNITED STATES PATENT OFFICE.

HARRY VISSERING, OF CHICAGO, ILLINOIS, ASSIGNOR TO HARRY VISSERING AND COMPANY, OF CHICAGO, ILLINOIS, A CORPORATION OF ILLINOIS.

UNCOUPLING DEVICE FOR COUPLINGS.

1,209,236.

Specification of Letters Patent. Patented Dec. 19, 1916.

Application filed March 22, 1911. Serial No. 616,253.

To all whom it may concern:

Be it known that I, HARRY VISSERING, a citizen of the United States, and a resident of Chicago, in the county of Cook and State 5 of Illinois, have invented certain new and useful Improvements in Uncoupling Devices for Couplings, of which the following is a specification.

My present invention relates to devices 10 for operating car coupler locks, and more particularly to improvements in the uncoupling levers commonly used in connection with automatic and other car couplers, and has special reference to the provision of an 15 improved type of that class of device which is operable from one side of the car to which it is applied.

The principal objects of my invention are the provision of an improved device characterized as above noted, which will readily accommodate itself to coupling pins of different locations relatively to the mounting of the operating lever, and a device so characterized which is thus accommodative as 25 well longitudinally as laterally, and to the movement of the draw bar both longitudinally and laterally; the provision of an improved device wherein the operating lever and the coöperating connecting link are 30 separable or otherwise disengageable to the end, first, that should either part become broken or so extensively bent in service that replacement of either part is required the discarding of the entire lock operating device will not be necessitated, and, second, 35 one wherein the connecting link may be used with other types of operating levers already applied to cars without requiring the demounting, or discarding of an entire device 40 in order to utilize and gain the advantages of my improvements; the provision of an improved connecting link which is most readily to be applied to coupling levers for their repair, and equally readily detachable, 45 and one which will not however become accidentally detached in service; the provision of an improved type of support adapted for use with the operating levers; together with such additional objects as may be hereinbelow disclosed.

In the attainment of the objects above mentioned, and in overcoming the disadvantages suggested, and in gaining certain further benefits which will hereinafter appear,

I have provided the constructions illustrated 55 in the accompanying drawings, wherein—

Figure 1 is a side elevational view of one embodiment of my improved form of link; and Fig. 2 is a side elevational view of a modified form of my improved link. 60

I have illustrated my link as connecting an eye 21 at the end of the operating lever to an eye 18 on the end of the coupler pin. The form of link shown in Fig. 1 comprises two members 41 and 42 provided with hooks 65 43 and 44 respectively, engaging the eyes 21 and 18, and having a flexible joint by means of the eyes 45 and 46 which should preferably be centrally located as shown in order to prevent flexion and opening, or flexion 70 and cramping of the device in operation. As a means for closing the hook ends 43 and 44 I make use of a spring 47 which is restrained from vertical movement by the resistance thereto interposed by the abutments 48 and 49 against which its ends press, such spring being put under compression toward the eye 21 and the parts flexed when it is desirable to disengage the eye 18 therefrom, or toward the eye 18 and the 80 parts flexed when it is desirable to disengage the eye 21 therefrom.

The device of Fig. 2 is similar to that of Fig. 1 save that where it is desirable to avoid any flexion of the parts 41 and 42 85 relatively to each other, such parts are made integrally rather than provided with the flexible connection indicated at 45 and 46.

It is believed that the operation of devices employing my invention will be understood by those skilled in the art to which it pertains without more exemplified description.

Having thus described my invention and illustrated its use, what I claim as new and 95 desire to secure by Letters Patent is the following:

1. In combination, a coupler having a locking device, a lever for operating said locking device, a disengageable connection 100 between said lever and locking device, and a spring on said connection requiring compression before said lever and said locking device can be disengaged whereby accidental disengagement of said connection is prevented.

2. In combination, a coupler having a locking device, a lever for operating said

locking device, a hooked member for dis-
engageably connecting said lever and lock-
ing device, and a spring surrounding said
member and normally extending beyond the
5 free end of said hook whereby accidental
disengagement of said member is prevented.

In testimony whereof I have hereunto

signed my name in the presence of the two
subscribed witnesses.

HARRY VISSERING.

Witnesses:

PAUL CARPENTER,
DONALD C. WILLIAMS.
